DRAW STRING BAG AND METHOD OF
MAKING THE SAME

Edward E. West, Richmond, Va.

Application July 29, 1931. Serial No. 553,742

8 Claims. (Cl. 150—11)

The present invention relates to draw string bags and more particularly to the construction at the mouths thereof and to the method of making the bag.

5 The principal objects of the invention are—to provide draw string bags which are neat in appearance and sturdy, in that they are not likely to rip at seams formed at marginal portions thereof; and to provide a method of making draw string bags by which production is facilitated, the operatives being able to do better work more rapidly than according to the usual methods which have been practiced for quite some time.

15 It is a usual practice in the making of a draw string bag to provide at the top margin of a blank, a hem extending from side to side, thread a string thru the passage formed by the hem so that the end portions of the string protrude from the hem passage at the sides of the blank; fold the blank along a medial line between the sides of the blank so that the openings of the hem passage are adjacent one another; sew a seam from the folded edge of the blank along the bottom and then along the meeting sides, but when approaching the hem, run or curve the line of stitching off to the side edge and not clear to the top, otherwise the thread may run thru or so closely to one or both of the runs of string in the hem passage as to prevent free drawing action; and finally turn the bag inside or right side out so that the raw marginal portions along the seam are inside the bag.

35 This results in a finished bag which is not neat in appearance. The mouth portion flares outwardly at one side of the bag where the line of stitches was run off in a curved path to the edge of the blank before reaching the top of the hem to avoid sewing the draw string tight. After the bag has been drawn closed, the tendency of a person when opening the bag is to use the index fingers projecting into the mouth of the bag to draw it open. If much force is exerted the result is that the bag will start to rip along the seam since the stitches terminate in a frail portion of the bag.

40 According to the present invention the hand grasping ends of the draw string are led out of the hem passage remote from the sides of the blank, preferably by slitting the hem inwardly from each side of the blank a distance to permit this leading out of the hand grasping end inwardly of a straight line paralleling the side edges of the folded blank, along which straight

line the stitches are made to the very top of the hem. As a result, the finished bag is neat in appearance for it is no wider at its mouth than at any other portion, and when the bag is opened in the manner above described, ripping 60 is resisted for the stitches are a sufficient distance remote from the raw edges of the bag body portion to not disrupt the fibres of the bag or disarrange the warp and weft of a fabric bag.

65 A part of the method may be carried out by use of the apparatus shown in my co-pending application for patent for Bag stringing machines, filed May 27th, 1930, Serial No. 456,138, by which strip material from which the bag 70 blanks are subsequently cut, is hemmed at one edge, the draw string material placed in the hem, the hem slit at spaced intervals and the draw string material drawn in loops thru the slits after which the strip material is severed and 75 the string material cut at the bight portions of the loops so that it is not necessary to string the hems after the blanks have been cut.

80 Other objects and advantages of the invention will appear in the following detailed description, taken in connection with the accompanying drawings, forming a part of this specification, and in which drawings,

Fig. 1 is a plan view of the bag material in strip form showing the hem and loops of draw 85 string material projecting therefrom, the dot and dash lines showing where the material may be cut to make the bag blanks.

Fig. 2 is an elevation of a bag blank.

Fig. 3 is a perspective view showing the blanks 90 folded with the sides near one another and the hand grasping ends of the draw string drawn back away from the sides of the main body of the bag opposite the folded side.

Fig. 4 is a perspective view showing the lines 95 of stitches along the bottom and the side margins of the bag body.

Fig. 5 is a perspective view of the finished bag, and

Fig. 6 is an enlarged fragmentary view in plan 100 and horizontal section showing the inturned seam and the slits thru which the draw string projects.

105 Similar characters of reference indicate corresponding parts in the several views.

Before explaining in detail the present improvement and mode of operation thereof, I desire to have it understood that the invention is not limited to the details of construction and arrangement of parts which are illustrated in the 110

accompanying drawings since the invention is capable of other embodiments, and that the phraseology which I employ is for the purpose of description and not of limitation.

5 In the drawings, A designates a strip of material, such as cloth, paper, etc., from which the bag blank B may be cut; C the draw string material from which the draw string D may be cut; E a line of stitches of a hem F; G a line of stitches of seam H along the bottom of the bag; and J a line of stitches of seam K along the side of the bag.

The strip of bag material is preferably of a width equal to the length of the desired bag, plus sufficient material to provide the hem F and the seam H. The hem F is provided by doubling the material upon itself one or more times and running a line of stitches E longitudinally of the strip providing a hem passage 7 to accommodate the draw string material C. This hem is provided with slits 8 at spaced intervals longitudinally of the hem thru which loops 9 of draw string material may be drawn, as shown in Fig. 1. Insofar as the present method is concerned, it makes no difference whether the slits 8 are provided before, during or after the hem is formed, however, in the aforesaid pending application is shown apparatus whereby the slits are provided after the hem is completely formed. The draw string material C may be laid or strung in the passage 7 of the hem before, during or after its formation and likewise the loops 9 may be drawn from the slits before, during or after completion of the hem.

35 The dot and dash lines 10 indicate where the bag material is cut transversely of the hem at the slit portions thereof and where the bight portions 11 of the loops 9 of draw string material are cut to provide the blank B shown in Fig. 2. 40 The cutting of the bag material and draw string may be simultaneous, or one may be cut in advance of the other. This cutting of the draw string material provides finger grasping ends 12 which extend from the slits 8 laterally of the hem, as shown in Fig. 2.

Taking the blank as shown in Fig. 2, if it is desired that the folded over portion 15 of the hem be ultimately on the inside of the finished bag, the bag body 13 is folded upon itself as shown at 14 in Fig. 3, with the folded over portion 15 of the hem outermost, the line of fold 14 being parallel to and midway between the end margins 16 of the bag body.

Prior to providing the lines of stitches G and H, the end margins 16 are brought together so that the slitted hem portions are in juxtaposed relation as shown in Fig. 4. It is immaterial whether the line of stitches G or J is first formed, or whether they are run off to the edges 60 at the bottom of the bag or continued without cutting the thread, one of the principal characteristics of the invention being the line of stitches 18 extending entirely across the hem F, so that the finger grasping ends 12 are between the seam K and the fold 14, as clearly shown in Fig. 4. In this connection it may be observed that the operative in making the bag may hold the ends 12 of the draw string so that they are out of the path of the needle and thread, and 70 the line of stitches J may continue straight across the hem F without liability of sewing or so confining the draw string in the passage 7 as to make drawing or puckering of the bag, when closing same, difficult. Much time is saved in 75 that the operative does not find it necessary to

observe the approach of the hem, as when sewing from the bottom toward the mouth 19 of the bag.

While the bag may be used in the condition shown in Fig. 4, it is preferably turned inside out, or right side out, as shown in Fig. 5, thus concealing the raw edges of the seams H and K. It will be noted from Fig. 5 that the bag is no wider at its mouth portion than at any other portion, thus providing a bag neat in appearance and reinforced against ripping since the line of stitches 18 extends entirely across the hem F, the finger grasping ends 12 of the draw string protruding from the slits 8 at points intermediate the seam K and the body fold 14.

80 It is to be understood that, by describing in detail herein any particular form, structure or arrangement, it is not intended to limit the invention beyond the terms of the several claims or the requirements of the prior art.

85 Having thus explained the nature of my said invention and described a way of constructing and using the same, although without attempting to set forth all of the forms in which it may be made, or all of the modes of its use, I claim: 90

1. A bag comprising a body portion having a seam along a side thereof and a hem at its top, said hem provided in its folded edge with slits extending to the edge of the seam, and a draw string in the passage of the hem, and having 105 finger grasping ends extending thru the inner end portions of the slits to the exterior of the hem.

2. A bag blank having a hem along one margin thereof, said hem provided in its folded edge 110 with a slit extending inwardly from each end thereof, and a draw string in the passage of the hem having finger grasping ends extending out of the slits laterally of the hem.

3. Those steps in the method of providing a 115 bag which consist in providing a blank with a hem along one edge, forming openings in the folded portion of the hem remote from the sides of the blank, then inserting a draw string in the passage of the hem with finger grasping ends extending out of the folded edge of the hem remote from the sides of the blank, doubling the blank upon itself to provide a bag body and so that the hem ends are adjacent one another, and stitching the bag body and hem to provide 120 a seam running entirely across the hem with the draw string between the seam and the body fold. 125

4. Those steps in the method of providing a bag which consist in providing a hem and a draw 130 string in the passage of the hem along the margin of the bag body material, slitting the hem at spaced points and drawing portions of the draw string from the slits to provide finger grasping portions extending laterally from the hem, doubling the body material upon itself so the slitted hem portions are in juxtaposed relation, and stitching the bag body across the hem with the finger grasping portions of the draw string between the line of stitches and the body fold. 135

5. Those steps in the method of providing a 140 bag which consist in providing a hem, forming openings in the folded portion of the hem remote from the sides of the blank, then inserting a draw string in the passage of the hem along the margin of bag body material, drawing portions of the draw string from the passage of the hem in the folded edge thereof to provide finger grasping portions extending laterally at spaced points from the hem, doubling the body material upon itself so that the portions of the hem from 145 150

which the finger grasping portions extend are in juxtaposed relation, and stitching the bag body across the hem with the finger grasping portions of the draw string between the line of 5 stitches and the body fold.

6. Those steps in the method of providing bag blanks which consist in providing a hem at the longitudinal margin of strip bag material and stringing a draw string in the passage of the 10 hem, slitting the hem at spaced apart intervals, drawing loops of draw string from the slits, cutting the bag material transversely of the hem at the slit portions thereof and the draw string at the bight portions of the loops.

15 7. Those steps in the method of providing bag blanks which consist in providing a slitted hem

at the longitudinal margin of strip bag material, the slits being spaced apart longitudinally of the hem and string a draw string in the passage of the hem, drawing loops of draw string material from the slits, and cutting the bag material 80 transversely of the hem at the slit portions thereof and draw string at the bight portions of the loops.

8. A bag folded from a bag blank and stitched along the free edges thereof opposite to the fold, said bag having a stitched hem with a draw string therein, said hem having in its folded edge an opening at two points extending inwardly from the stitched edges for the passage of the ends of the string therethrough.
